UNITED STATES PATENT OFFICE.

JOHN TAMAS, OF CLEVELAND, OHIO.

SECURITY-POCKET.

1,257,048.

Specification of Letters Patent. Patented Feb. 19, 1918.

Application filed March 21, 1917. Serial No. 156,237.

To all whom it may concern:

Be it known that I, JOHN TAMAS, a subject of the King of Hungary, resident of S. E. Cleveland, county of Cuyahoga, and 5 State of Ohio, have invented certain new and useful Improvements in Security-Pockets, of which the following is a specification.

This invention relates to improvements in garments, and particularly to the pockets thereof, and has as its principal object the provision of a plurality of compartments within the pocket, each of the compartments being suitable for holding miscellaneous objects separately, such as coins, 10 bills, or other valuables entirely distinct from the main pocket, the object being to prevent unauthorized or unwarranted intrusion, and possible subsequent loss.

This and other like objects are attained 20 by the novel design and construction of parts hereafter described and shown in the accompanying drawings, forming a material part of this specification, and in which:—

Figure 1 is a side elevational view of a 25 gentleman's coat made in accordance with the invention, the pocket being indicated by broken lines.

Fig. 2 is an enlarged fragmental front 30 view of the same, parts being broken away to show the interior.

Fig. 3 is a vertical sectional view taken on line 3—3 of Fig. 2, and

Fig. 4 is a similar view taken on line 4—4 of Fig. 2.

The material of the garment 10 is here 35 shown to be of relatively heavy quality provided with an ordinary flap 11 cut transversely as at 12 allowing for the passage of the fingers or hand in entering the pocket.

Secured to the inner side of the material 40 10 are the walls 14 and 15 of the pocket proper having between them a space 16 in which may be placed any articles which it is desired to carry, as handkerchiefs, gloves, 45 etc., while secured to the wall 15, constituting the inner portion of the pocket, is an auxiliary wall 18 having a space 19 between it and the wall 15, the opening to the space 19 being normally covered by a flap 20 engaged along its upper edges so that merely

inserting the fingers in the pocket space 16 does not disclose the opening to the inner pocket.

Extending from edge to edge of the pocket 19 is an elastic flexible element 22, the same 55 being securely held at its ends and so arranged as to hold the wall 18 closely against the main wall 15, and in one of the upper corners of the pocket is provided a third compartment 25, the walls of which are 60 stitched together along the bottom 26 and side edge 27, forming in effect a plurality of minor compartments susceptible of receiving coins or the like which are prevented from issuing by the flap 20 as is the main 65 portion of the second interior compartment which will be clearly seen from an inspection of Figs. 3 and 4.

In operation, the flap 11 having been raised, and the fingers inserted through the 70 slit 12 into the main pocket, small articles may be entered or withdrawn therefrom with entire freedom and without in anyway interfering with the interior compartment, the wall 18 and flap 20 of which act as a 75 baffle against entering, the slits open to the compartments, being held in normal closed relation by the elastic element 22.

From the foregoing, it will be seen that a 80 secure and substantially rubber-proof pocket has been disclosed which can be applied to any garment by any ordinary tailor or seamstress without material changes in the garment of any kind.

Having thus described my invention, what 85 I claim as new, and desire to secure by Letters Patent, is:—

The combination with a garment having a main pocket therein, a flap for said pocket, said flap normally covering the entrance 90 thereto, of an interior supplementary pocket secured inside said main pocket, a flap therefor, an elastic means for closing the opening to said interior pocket, and a plurality of internal compartments formed within said 95 interior pocket.

In testimony whereof I have affixed my signature.

JOHN TAMAS.

Copies of this patent may be obtained for five cents each, by addressing the "Commissioner of Patents, Washington, D. C."
